SET-RESET INDICATOR AND VARIABLE DIGIT COUNTER AND INDICATOR

Francis J. Cerulli, Berkeley Heights, N.J., assignor to the United States of America as represented by the Secretary of the Army

Filed Oct. 17, 1962, Ser. No. 231,309

6 Claims. (Cl. 235—92)

This invention relates to electronic digital counting and indicating devices, in general, and more particularly to such devices which can perform a plurality of functions with only a minimum of change in the basic package.

The package to be described herein has three distinct applications. These are specifically: a set-reset indicator, a variable digit counter indicator and a variable digit counter. The set-reset indicator is used to accept, store and display information when commanded to do so. The variable digit counter indicator is a counter which will display its own progress. The variable digit counter will also count, but because of its decimal output it can be used in timing and other associated logic functions.

Presently marketed counter units are single function devices with none of the features for multiple function use which this device incorporates. The capability of changing from one counter configuration to another with only minor wiring changes presents an advantage over known circuits. Most of the wiring changes can be accomplished by switching while some of the changes in circuitry can be effected by substituting one plug-in unit for another. Of course, if the basic package were to be used in only one of the possible modifications, the changes could be made by manually resoldering the connections.

It is accordingly an object of this invention to provide a digital counter package which may be readily modified to perform a plurality of functions.

A further object of this invention is to provide a digital device for use in rapid data reduction especially where monitoring of the processed data is of value.

Another object of this invention is to provide a digital counter package which can function as a set-reset indicator, a variable digit counter indicator or a variable digit counter.

Other objects and advantages of this invention will be more readily comprehended upon consideration of the following detailed description of the invention taken in conjunction with the accompanying drawings wherein:

FIGS. 1A and B are a circuit diagram of the basic package of the multi-function digital equipment in accordance with the present invention.

FIG. 2 is an NPN transistor which may be substituted for the PNP transistor T_2 in FIG. 1B, and

FIG. 3 is a circuit diagram of the output drivers and socket which replace the output drivers and Nixie tube of FIG. 1A when the circuit is to be used as a variable digit counter.

Referring now to FIGS. 1A and B there is shown a four stage binary chain having flip-flops 41, 42, 43 and 44 comprising transistors T_3 and T_4 , T_5 and T_6 , T_7 and T_8 and T_9 and T_{10} , respectively, along with their associated circuitry. The input of each flip-flop is provided with an AND gate. The first flip-flop, which comprises transistors T_3 and T_4 , has an input AND gate comprising diodes D_{15} and D_{16} and resistor R_{40} . The other three flip-flops have similar gates comprising diodes D_{17} through D_{22} and resistors R_{41} , R_{42} and R_{43} . The outputs of these gates are A.C. coupled into the respective flip-flops through capacitors C_{10} through C_{17} . Capacitors C_{10} , C_{12} , C_{14} and C_{16} can be switched in or out of the circuit depending on the desired operation. The AND gates have a common leg 11 which connects the output of transistor T_2 of an inhibit

generator 34 to one of the inputs of each gate. The remaining inputs of the gates are connected to pins A, J, K and B respectively of connector 2. Pins C, D and H of this connector supply operating voltages to the transistors while pins E, F and L are pulse input terminals.

A reset generator 35 comprises a transistor T_1 , the emitter of which is connected to the bases of transistors T_3 , T_5 , T_7 and T_9 through diodes D_{11} through D_{14} . Switches S_1 , S_2 , S_3 , S_4 and S_5 are used to insert or short out various circuit components depending upon the desired operation of the circuit. Capacitor C_1 and diode D_1 act as part of the reset generator circuitry when the package is used as a counter. Point U is connected to the base of transistor T_2 through a diode D_2 and a resistor R_6 .

The outputs of the eight flip-flop transistors are connected through lines 12 to 19 to a resistor matrix comprising resistors R_{16} through R_{55} . The matrix output voltages which appear at points 21 through 30 are connected to high voltage NPN transistors T_{11} through T_{20} , which are connected to the cathodes of a Nixie tube V_1 . The anode 32 of the Nixie tube is connected through resistor R_{13} to a source of positive voltage at pin L of connector 1. Pin K of this connector is grounded and the remainder of the pins are connected to the outputs of each of the eight transistors of the binary chain.

The first configuration to be discussed will be the set-reset indicator, considering the following instructions with respect to modifying FIG. 1. Capacitors C_{10} , C_{12} , C_{14} and C_{16} are to be switched out of the circuit. Point S is connected to point T by closing switch S_2 , switch S_1 remaining open. Point U remains unconnected. Resistor R_{44} is omitted from the base biasing circuit of T_2 by opening switch S_3 . Resistor R_5 is shorted by closing switch S_4 . Transistor T_2 must be replaced by the NPN transistor shown in FIG. 2. It is to be noted that the transistor of FIG. 2 is connected to points M, N and O of FIG. 1 so that its emitter is connected to point M and its collector to point N. Thus the circuit has been changed from an inverting PNP amplifier operating between ± 12 volts to an NPN emitter follower operating between ground and -12 volts.

The set-reset indicator will accept binary coded decimal (BCD) information, on four parallel lines, retain it in storage for as long as required, decode said information, and display the decimal information by means of a Nixie tube. FIG. 1 shows decoding of a 1-2-4-8 code; however, any binary code may be used.

Flip-flops 41 to 44 will trigger on a positive edge and are in saturated operation.

The logical levels for all inputs and outputs are as follows: a "0" is represented by 0 to -2 volts and a "1" is represented by -7 to -12 volts. Hence, to raise the common leg 11 of the input gates to the -12 volt condition, the set-enable input E of connector 2 must be brought to the "1" condition, i.e., a negative pulse between -7 and -12 volts is applied to the base of emitter follower T_2 causing a negative pulse to appear at common line 11. This will enable the flip-flops to accept the information available at the other leg of the input AND gates from terminals A, J, K and B of connector 2. It must be realized that the input to the gates must be a negative level for the period of time that the gates are turned on. The minimum time duration of this operation is $5 \mu\text{sec}$. The flip-flops have now accepted information. At some later time when new information is available, a positive pulse of at least $5 \mu\text{sec}$. duration applied to the input, called "reset in," will reset the flip-flops to the "0" state due to conduction of emitter follower T_1 of the reset generator. Immediately following reset new information may be accepted. The resetting of the flip-flops is accomplished by forcing the bases of the

"0" transistors positive. In the set-reset indicator, configuration, the 2° input pin F of connector 2 is not used.

The resistive matrix accepts the flip-flop outputs by means of lines 12 to 19. The matrix output then controls a high voltage NPN transistor that activates one of the cathodes of the Nixie tube. Two basic facts are used to advantage in the circuit that allows operating Nixies from small signals. These being that the Nixie will operate at low pre-bias voltages and the uniqueness of the collector breakdown potential of certain NPN transistors. In essence, the matrix and the transistor act the same as any NOR logic element. Detection of all "0's" by any particular group of resistors in the overall matrix will turn on its particular transistor. This will increase the potential between the centered anode 32 and the particular cathode until the gas in the tube ionizes and the cathode glows. A glance at FIGURE 1 will show that the flip-flop outputs are made available at connector #1 for use in other control circuitry if needed.

The other configuration using the Nixie display is the variable digit counter indicator which uses the circuit of FIG. 1 modified as follows: C_{10} , C_{12} , C_{14} and C_{16} are switched into the circuit. Point R is connected to point S by closing switch S_1 , switch S_2 being open. Switch S_3 is to be closed and switch S_4 opened. The set-enable connection at pin E of connector 2 cannot be more negative than 0 volts. Presetting the count is accomplished by moving point U of the inhibit generator to the output of one of the Nixie driving transistors T_{11} to T_{20} . These outputs are conveniently located for this purpose in order that the change of count may be done in a minimum of time. T_2 is a PNP transistor as shown in FIG. 1.

The variable digit counter indicator will accept a serial pulse train and count the pulses, displaying on the Nixie tube the number of pulses having been counted. This unit will count to any number from 1 to 9 and then automatically re-set itself to zero after the next input pulse. The usefulness of this scheme can be seen, for example, on a 24-hour digital clock. The clock would consist of six packages that would display time as follows: 23 hours, 59 minutes, 59 seconds. Three of the units would be set for automatic reset at 9, 2 at 5, and 1 at 2. Hence, if the clock were reading 23, -59-59, the next input would reset the seconds and minute counters to zero. With the use of one NOR logic element reset of the least significant hours counter can be accomplished which would reset the most significant hours counter.

The four input capacitors C_{10} , C_{12} , C_{14} and C_{16} are added to make each flip-flop a triggered flip-flop or scale of two circuits. The serial pulse train to be countered is applied to the "set 2° or trigger in" input at pin A of connector 2, and a jumper is placed on the connector from pin A to pin F by closing switch S_5 . Connecting B to A of the inhibit generator will hold the common leg of the input AND gates at -12 volts when T_2 is off and +1 volt when T_2 is on. Bringing the gate slightly positive by properly selecting the values of resistors R_4 and R_5 assures a solid clamp. The inhibit generator receives its input when point U is connected to one of the collector outputs of the Nixie drivers.

The first flip-flop receives its input in the form of a serial pulse train. The output of this flip-flop is inserted into the input of flip-flop 2 by taking the 2° side, pin C of connector 1 and connecting it to pin J of connector 2. The remaining flip-flops are connected accordingly.

Now, assuming the counter was preset to 9, i.e. point U is connected to the collector of transistor T_{20} , when the nine driver T_{20} turns on, point U will drop sharply to ground. This will turn T_2 on and inhibit all input gates. Meanwhile, by virtue of D_1 , the base of T_1 is pre-biased so that the next input pulse through C_1 will turn on T_1 . This will reset the flip-flops to the zero state and put T_2 into the enable condition in order that the counter may accept pulses. The above approach is taken to insure that no commutating pulses will set flip-flops at any

chosen reset position. The counter may still be reset at anytime by the application of a positive pulse at the reset input. The same is true of the inhibit generator.

The third configuration is also a counter, however, the individual decimal outputs are made available at an output connector as shown in FIG. 3. In FIG. 1 certain changes must be made for this configuration.

Point S is connected to point T by closing switch S_2 , switch S_1 remaining open. Capacitors C_{10} , C_{12} , C_{14} and C_{16} are inserted into the circuit. Switches S_3 and S_4 are closed. Transistor T_2 is a PNP type connected in a common emitter configuration as shown in FIG. 1. Care must be taken to prevent grounding the case since the particular transistor used has its base connection tied to the external case for heat dissipation reasons. The accidental grounding of the case would damage the transistor.

The output stage shown in FIG. 3 is to be substituted for that of FIG. 1. The PNP output transistors 21 to 30 are inserted into FIG. 1 at points 20 to 31 in place of the NPN transistors. Pin L of connector 1 must be connected to -12 volts to provide the proper bias voltage for these transistors. A standard eleven pin tube socket 33 makes available the individual decimal outputs. The decimal outputs have logical levels of 0 and -12 volts making it compatible with the transistor circuitry used throughout the system. The theory of operation of the inhibit and reset generators is similar to that mentioned in the preceding section, but certain structural changes must be made for the following reasons: The output transistors T_{11} to T_{20} of the counter indicator are NPN with grounded emitters. Thus the outputs of these transistors swing between +12 volts and 0 volts. One of these transistors is chosen to drive point U of the inhibit generator. The inhibit generator being an NPN emitter follower has an output which swings from -12 volts to +12 volts. The tap between resistors R_4 and R_5 , the emitter follower resistors, allows the bias of transistor T_1 to approach ground and not +12 volts.

When the package is used as a variable digit counter the functions of T_1 and T_2 remain the same with the exception of the voltage levels. Since the output transistors of this configuration are of the PNP type having output voltages varying from -12 to ground, T_2 voltages must be changed accordingly. Thus the emitter of transistor T_2 is grounded. Resistor R_5 must be shorted to allow the R_4 - R_5 tap point to reach the T_1 bias level of nearly 0 volts. If R_5 were not shorted, the tap between resistors R_4 and R_5 would swing from -12 volts to -6 volts rather than from -12 volts to ground.

The invention thus comprises a basic circuit which can be readily modified so that three different functions can be performed. Operation could be changed by manually resoldering the connections or external switches could be used.

What is claimed is:

1. A multifunction binary circuit comprising a plurality of binary flip-flop stages each having an input AND gate; an inhibit generator transistor having an input terminal, an output terminal and a common terminal; means for supplying operating potentials of a reference potential, a voltage more negative than said reference potential and a voltage more positive than said reference potential; switch means connecting said common terminal to said positive potential of said reference potential; a first resistor and a first switch connected in series between said common terminal and said input terminal; a second resistor having one terminal connected to said output terminal; a third resistor connected between said negative potential and the terminal of said second resistor that is remote from said output terminal; a second switch connected in shunt with said second resistor; and means to connect the junction of said second and third resistors to each of said AND gates.
2. The binary circuit of claim 1 which further com-

prises resistor matrix means for converting binary signals to a decimal output; the outputs of said plurality of flip-flop stages being connected to said matrix; a plurality of output transistors having input and output terminals, the input terminals of said output transistors being connected to said matrix; the output terminal of one of said output transistors being connected to said inhibitor transistor input terminal; and output means connected to each of said output transistor output terminals.

3. The binary circuit of claim 2 in which said output means is a Nixie indicator.

4. The binary circuit of claim 2 in which said output means is an output connector.

5. A binary circuit comprising a plurality of binary flip-flop stages each having an input AND gate; an inhibit generator transistor having an input terminal and an output terminal; a reset generator transistor having an input terminal and an output terminal; biasing means connected to said reset transistor input terminal for holding the reset transistor in a normally non-conducting condition; a circuit input terminal connected to said biasing means and the AND gate of the first of said flip-flop

stages; a diode connecting said inhibitor transistor output terminal to said biasing means; means connecting said reset transistor output to each of said flip-flop stages; means connecting said inhibit transistor output to each of said input AND gates; resistor matrix means for converting binary signals to a decimal output, the outputs of said plurality of flip-flop stages being connected to said matrix; a plurality of output transistors having input and output terminals, the input terminals of said output transistors being connected to said matrix, and the output terminal of one of said output transistors being connected to said inhibit transistor input transistor.

10 15 6. The binary circuit of claim 5 wherein said biasing circuit comprises two series connected resistors connected to said reset transistor input terminal, the junction between said resistors being connected to said diode and said circuit input terminal.
